(57) **CLAIM**

The ornamental design for an electric motor, as shown and described.

DESCRIPTION

FIG. 1 is a top, front, right side perspective view of an electric motor, showing our new design;

FIG. 2 is a top, rear, right side perspective view thereof;

FIG. 3 is a right side elevation view thereof;

FIG. 4 is a bottom, front, left side perspective view thereof;

FIG. 5 is a top plan view thereof; and,

FIG. 6 is a front elevation view thereof.

The broken lines in the drawings depict portions of the electric motor that form no part of the claimed design.

1 Claim, 6 Drawing Sheets
